(57) CLAIM

The ornamental design for a combined hanging basket and wind chimes, as shown and described.

DESCRIPTION

FIG. 1 is an enlarged top view of the combined hanging basket and wind chimes, showing my new design;

FIG. 2 is a right view;

FIG. 3 is a left view;

FIG. 4 is a front view;

FIG. 5 is a rear view; and,

FIG. 6 is an enlarged bottom view.

The broken lines illustrate portions of the combined hanging basket and wind chimes that form no part of the claimed design.
